UNITED STATES PATENT OFFICE.

CHARLES EDWARD GREEN AND THOMAS HENRY GREEN, OF LONDON,
ENGLAND.

CANDLE-LAMP.

SPECIFICATION forming part of Letters Patent No. 566,755, dated September 1, 1896.

Application filed November 2, 1895. Serial No. 567,711. (No model.) Patented in England March 6, 1895, No. 4,795, and in France October 21, 1895, No. 251,094.

To all whom it may concern:

Be it known that we, CHARLES EDWARD GREEN and THOMAS HENRY GREEN, subjects of the Queen of Great Britain, and residents 5 of 49 Hatton Garden, London, England, have invented certain new and useful Improvements in or Relating to Candle-Lamps, (patented in Great Britain, No. 4,795, dated March 6, 1895, and in France, No. 251,094, dated 10 October 21, 1895,) of which the following is a specification.

The object of this invention is to utilize certain known detail appliances in conjunction with an unbreakable exterior in imitation 15 of a candle of any desired color.

For the purpose of this invention we make what is termed a "candle-lamp" of a metal tube open at one end for the reception of a screw-ferrule, which has as part thereof a 20 bezel ring or fillet as a projecting bead for the double purpose of giving finish and for securing an exterior tube upon the metal tube. This ferrule is provided with a socket or plug, also screw-threaded for a screw-pin 25 to be rotated up and down in, said pin having a head to prevent its withdrawal and also a triangle or square tapered socket-piece which can move in or between a series of bent strips in order to expand them to fit large-size 30 candlesticks and to contract by reversing the rotation of the screw expander.

In lieu of the expansible strips a rubber socket or thimble can be used, also capable of expansion by the expanding socket-piece, 35 or such thimble may be tapered and be corrugated on the outside for self-adjustment and for holding power in a candlestick when placed in position.

The upper end of the metal tube has a fixed 40 bezel ring or fillet with an undercut or channel for the reception of one end of a celluloid, xylonite, or equivalent tube, or said outer tube may be of toughened glass or other material of a color corresponding to a fancy or 45 other candle, the whole being surmounted by a socket, shade-holder, extinguisher, or the like, as desired.

The candle proper of any kind is within the metal tube and is pushed up by a spring

to compensate for the combustion in a manner well known.

Our invention is represented in the annexed drawings.

Figure 1 is a section, Fig. 2 part elevation, and Fig. 3 perspective elevation, of collapsible socket-plug with rim; Fig. 4, section of socket-plug, wings contracted; Fig. 5, section of socket-plug, wings expanded; Fig. 6, bottom plan, and Fig. 7 elevation, of candle-lamp with conical fluted rubber plug and shade-holder; Fig. 8, detached elevation of fluted rubber plug with rim.

A is a metal tube; B, a ferrule; C, a bezel-ring with turned-up and inwardly-curved outer edge as part of ferrule, forming an annular recess for reception of lower end of tube A and exterior tube D, of glass, celluloid, or other material stained or colored to represent a fancy-colored or a plain candle; E, a screw-threaded pin centrally arranged in ferrule C 65 for up-and-down motion therein. The lower end of the screw-threaded pin E is formed with a head F and occupies a position in a square cone or equivalent shaped socket-piece G, the spread-out portion of the socket-piece 70 serving to expand the wings H H, which by their springiness and form cleave to the sides of same, so that the wings are capable of being expanded or collapsed by being turned to the left or to the right to fit the socket of a candlestick, a chandelier, or wall-bracket.

I is a top rim of tube A, having an under annular channel for the reception of the upper end of the glass, celluloid, or other exterior tube D. Above the rim I the tube A 85 is punched from the inside to form a couple of projections J J for engagement in the bayonet-shaped slots K K of the nozzle L, which locates the candle proper, M, this being kept up to the shoulder N of the cap as consumption progresses by the helical spring P, which is within the tube A and bearing on the inner flange of the tube A.

The outside diameter of the cap L coincides with the interior diameter of the band 95 Q of the shade-holder R, this being composed of two curved legs S S, connecting the band Q with the crown of the holder, on

which a paper or other fancy cone or other shaped eye-screen can be dropped. One of the legs S of the shade-holder has an extinguisher-lever T pin-jointed to it in such 5 manner that when the cup U is up it hangs back slightly beyond a vertical line and bears against the leg, partially retained there by the chain V and weight W until it is found necessary for extinguishing the candle, when 10 the cap can be thrown over or lowered onto the wick to extinguish the flame.

As a modification or in substitution for the 15 extinguisher-lever T, we purpose making a conical-ended plug with the rim C and a central screw-threaded portion B and to employ therewith a fluted rubber cone-shaped tip X, the strew-threaded center engaging the screw-thread at the lower end of the tube A.

The cone-shaped fluted rubber tip X will 20 enable the candle-lamp to be used without the extinguisher-lever T. In either case the same facilities are offered for the fitting within the socket of a candlestick, chandelier, or a wall-bracket.

What we claim, and desire to secure by 25 Letters Patent, is—

1. In a candle-lamp, the combination of inner tube A, loose-fitting outer tube D, screw-ferrule ring B, C, central screw-pin E, inclined-face socket-piece G, expandible wings 30 H, H, internal spring P, fixed upper rim I, nozzle L, shade-holder Q, R, S, with extinguishing-cup U, and weighted chain V, as specified and substantially as shown.

2. In a candle-lamp, fixed inner tube A, 35 outer loose tube D held in position between fixed rim I and adjustable ferrule-ring B, C, said ferrule-ring having central screw-pin E, socket G, expanding wings H, H, as specified and substantially as shown.

In witness whereof we have hereto signed our names, in the presence of two subscribing witnesses, this 9th day of October, 1895.

CHARLES EDWARD GREEN.

THOMAS HENRY GREEN.
